UNITED STATES PATENT OFFICE.

OLIVER P. GREENSTREET, OF OWENSVILLE, MISSOURI, ASSIGNOR OF ONE-FOURTH TO WALTER H. OBERG, OF ST. LOUIS, MISSOURI, AND ONE-FOURTH TO JOSEPH T. TATE, OF OWENSVILLE, MISSOURI.

CLOTHES WASHER.

Application filed March 27, 1926. Serial No. 97,935.

This invention relates to those washing devices which are intended to be disposed within an ordinary clothes boiler and which are provided with pipes or conduits connected to a chamber disposed in the lower portion of the boiler, the boiling water rising up through these pipes or conduits and being discharged downward through the clothes to thus dislodge the dirt therefrom. The general object of the present invention is to provide a washing device of this character which is very simple in construction, which is effective in use and particularly which is so constructed that it may be readily cleaned.

My invention is illustrated in the accompanying drawings, wherein:—

Figure 1 is a vertical section of a clothes washer constructed in accordance with my invention, the clothes boiler being in section;

Fig. 2 is an elevation of the washer.

Referring to these drawings it will be seen that my washing device comprises a chamber formed by a wall 10 having a depending flange 11, this chamber being adapted to rest upon or be supported slightly above the bottom of an ordinary wash boiler A. Extending upward from the wall 10 of this chamber is a pipe 12, which has screw-threaded engagement with a boss 13 extending upward from the wall 10.

Detachably engaged with the upper end of the pipe 12 is a cross pipe 14, this pipe having at its middle an interiorly threaded boss 15 engageable with the threaded upper end of the pipe 12. The pipe 14 at its ends has screw-threaded plugs 16, having legs on their outer ends whereby a wrench may be applied to remove the plugs. The pipe 14

is provided with downwardly opening 40 perforations 17.

This device in use is placed within a boiler, as illustrated in Figure 1, the boiling water is forced upward through the pipe 12 and along the pipe 14 and is discharged 45 through the perforations 17 in the form of jets. Thus there is a continual circulation of boiling water through the clothes. The pipe 14 may be readily cleaned by removing the plugs 16. The pipe 14 may be removed 50 from the pipe 12 to permit this pipe to be cleaned and if desired this pipe 12 may be removed from the inverted chamber 10.

I claim:—

A clothes washer of the character described comprising a chamber open at the bottom and defined by a horizontally disposed wall and depending flanges at the sides and ends of said wall, the wall having depending lugs whereby to support the 55 chamber in spaced relation from the bottom of a wash boiler, an internally threaded boss formed on the upper side of the horizontal wall and disposed centrally thereof, a vertically extending pipe extending upward from the chamber and having its lower 60 end threaded into said boss, a cross pipe having an interiorly threaded boss for receiving the upper end of said first named pipe and having a length approximately equal to the 65 length of the chamber, removable plugs normally closing the ends of the cross pipe, the under face of the cross pipe having a plurality of spaced perforations therein.

In testimony whereof I hereunto affix my 70 signature.

OLIVER P. GREENSTREET.
